UNITED STATES PATENT OFFICE.

CHARLES HENRY FRENCH, OF CANTON, MASSACHUSETTS, ASSIGNOR TO FRENCH & WARD,
OF NEW YORK, N. Y., A FIRM.

DESIGN FOR A KNIT FABRIC.

No. 39,334.

Specification for Design.

Patented June 2, 1908.

Application filed February 28, 1908. Serial No. 418,403. Term of patent 7 years.

To all whom it may concern:

Be it known that I, CHARLES H. FRENCH, a citizen of the United States, residing at Canton, in the county of Norfolk and State of Massachusetts, have invented a new, original, and ornamental Design for a Knit Fabric, of which the following is a specification, reference being had to the accompanying drawing, forming a part thereof.

The figure is a face view of a knit fabric showing my design.

I claim:

The ornamental design for a knit fabric as shown.

CHARLES HENRY FRENCH.
